UNITED STATES PATENT OFFICE.

ORVILLE W. VAN DENBURGH, OF SCHUYLERVILLE, NEW YORK.

PAINTER'S JACK.

SPECIFICATION forming part of Letters Patent No. 329,243, dated October 27, 1885.

Application filed August 10, 1885. Serial No. 174,063. (No model.)

To all whom it may concern:

Be it known that I, ORVILLE W. VAN DENBURGH, a citizen of the United States, residing at Schuylerville, in the county of Saratoga and 5 State of New York, have invented certain new and useful Improvements in Vehicle-Body Holders or Jacks, of which the following is a specification, reference being had therein to the accompanying drawings.

10 My invention relates to what I designate as a "body-tumbler" for light vehicles. It is a machine to be used principally in the paint-shop of carriage-factories, and is so constructed that a light body may be secured to it, and 15 then said body made to change its relative position to the painter, whereby he is enabled to work with greater ease and facility than when the body is simply placed upon a trestle.

20 In the accompanying drawings, which make a part of this specification, Figure 1 represents a side view, and Fig. 2 an end view, of my invention.

In the figures, A represents a sill, into 25 which are mortised at each end the cross bars or sills B B. These parts are firmly braced together, not only by the braces a a, but by similar horizontal ones, (marked a' a').

30 C C represent two standards, which are framed into the cross-sills B B, and which carry in suitable bearings in their upper ends the cross-shaft C'.

D represents a gear-wheel, which has a bearing in one of the standards C, and E is 35 a smaller wheel, which gears into wheel D, said wheel E being secured upon one end of the shaft C'.

F represents a detent connected by loops or staples to one end of the standards, and 40 which is pressed upward by a spring, c, and capable or adapted to be pressed downward by means of the levers b b'. The upper end of this detent is adapted to enter between the teeth of the gear-wheel D and retain it 45 at any desired point in its rotation. It will be seen that the lever G' is connected to the spring c.

The shaft C' is provided at its center with a bolster, I, said bolster being secured to

the shaft by means of a bolt, J, and a lever-nut, d.

K K represent two set-screws, which pass through the shaft, and which are intended to steady and brace the bolster. Guides l l are secured upon the shaft C' to assist in keeping the body in place.

H represents the body to be operated upon. It is taken green from the carpenter's shop and placed upon this machine in the paint-shop. The body is first placed upon the bolster I and is there secured either by screws or clamps which pass through its bottom. The painter then takes his stand at one side of the machine, and after painting one side he places his foot upon one of the levers G and removes or presses down the detent F from the teeth of wheel D. Said wheel is then turned, and through wheel E the shaft C' is partially revolved and sufficient to suit the wants of the operator.

By loosening up the hand-nut d the body may be revolved about bolt J as a center. The body by the two adjustments is easily adapted to the convenience of the painter, and that, too, without the necessity of having once to remove his paint-bucket.

It is evident that this device may be used for other purposes than holding light vehicle-bodies. I find that I can use it with equal results for running-gears. It can also be 80 used to advantage by cabinet-makers, house-painters, (for doors, blinds, &c.,) &c. One of the bolsters is attached by means of screws or clamps to each article to be painted. After the painting, the hand-nut d is removed, 85 and the article, with bolster attached, is taken from the shaft and set aside to dry.

The letter F indicates a bent iron bar secured between the shaft and the bolster and having the bolt J passing through it. The ends rest 90 on the bottom of the body and serve to steady the same.

Having thus fully described my invention, what I claim, and desire to secure by Letters Patent, is—

In a machine for holding and adjusting vehicle-bodies, articles of furniture, &c., during the operation of being painted, a frame,

substantially as herein described, said frame being provided with a revolving bar, gear-wheels and an adjusting-pawl, combined and used with a bolster or bar which is connected to the article to be painted and secured to the revolving bar, the several parts being so constructed and arranged that any desired position or adjustment may be given to the article to be painted, as is herein set forth.

In testimony whereof I affix my signature to in presence of two witnesses.

ORVILLE W. VAN DENBURGH.
